UNITED STATES PATENT OFFICE

WALDO J. GUILD AND ALFRED P. BURNS, OF WORCESTER, MASSACHUSETTS, ASSIGNEES
TO THE HEALD MACHINE COMPANY, OF WORCESTER, MASSACHUSETTS, A COR-
PORATION OF MASSACHUSETTS

GRINDING MACHINE

Application filed May 31, 1929. Serial No. 367,401.

The invention relates to grinding machines, particularly to automatic internal grinding machines. The invention involves certain improvements in machine organization and arrangement and combination of instrumentalities which can best be understood by reference to the disclosures of certain patents and patent applications on similar machines. Automatic precision grinding, particularly for internal work, and to within very close limits, was made possible largely by the invention of J. G. McDonough, as disclosed in Reissue Letters Patent No. 16,141, dated August 11, 1925. According to the said McDonough invention, a gauge, preferably revolving at the same speed as the workpiece, is maintained in position to enter that end of the workpiece bore which is opposite the end entered by the grinding wheel; when the grinding operation of said wheel enlarges the bore sufficiently for the gauge to enter therein, the machine, in response to such entry movement, procures withdrawal of the grinding wheel from said bore, to permit removal of the finished workpiece from the machine.

The possibility of error in such precision grinding is further reduced, as described in Kempton and Gallimore Patent No. 1,731,719, dated October 15, 1929, by causing the grinding wheel to be withdrawn from the workpiece just before the final and finishing cuts are taken, and subjected to a dressing operation, in order that the said final and finishing cuts may be taken with a sharp cutting and perfectly cylindrical grinding wheel.

In the aforesaid Kempton and Gallimore patent, a gauge is used to automatically inaugurate this intermediate dressing of the wheel. However, according to the invention of Guild Patent No. 1,682,672, dated October 28, 1928, this intermediate dressing operation may be automatically inaugurated by movement of the cross feed slide of the machine; that is, the position of the cross slide itself determines, in the grinding of each workpiece, when the dressing operation shall occur, suitable compensating means being provided to advance this position for suc-

cessive grinding operations, in order to make each dressing operation effective on the grinding wheel.

For increasing the rate of production of such automatic machines, the copending application of Highberg, Serial No. 99,287, filed April 2, 1926, discloses an automatic work loader adapted to take a fresh workpiece from a magazine and place it in the chuck at the completion of every grinding operation. In such a machine, equipped with gauging or sizing devices according to the aforesaid patents, the grinding proceeds automatically until the magazine or hopper supplying the workpiece is exhausted of workpieces, or the grinding wheel itself is dressed beyond its usable limits.

The present invention is an improvement on the aforesaid prior inventions, and combines the best features of each. According to the present invention, cross slide operating means is depended upon to inaugurate the dressing stroke to dress and true the grinding wheel, thereby dispensing with one of the separate gauges used in the Kempton and Gallimore patent. The final runout of the grinding table, however, is made responsive to a rotating gauge of the McDonough type, since this is the most accurate known method of fixing the size of a workpiece. It will thus be seen, that the machine retains to the fullest extent the advantages of the McDonough reissue patent principle, coupled with the advantages of an automatic dressing stroke, just prior to the coming to size of the workpiece in accordance with the patent of Kempton and Gallimore, together with the simplicity of operation of this function as shown in the patent to Guild. The foregoing, accordingly, is one object of the invention.

In the Kempton and Gallimore patent, means are provided to decrease the rate of cross feed for the grinding cuts taken after the dressing operation. We have discovered that precision grinding is further facilitated by removing all spring in the wheel spindle prior to the dressing operation, since the amount of material which is removed from the grinding wheel is thus made more nearly

a constant quantity. Another object of the invention, therefore, is to provide means for reducing the amount of cross feed between the grinding wheel and the work before the 5 dressing operation takes place.

A work loading mechanism operating according to the principle of the aforesaid Highborg application is disclosed in the accompanying drawings, but not described in 10 detail, because it does not differ in function or mode of operation from the work loader shown in said application. It is illustrated merely to make the machine complete and to give utility to various other mechanisms 15 which are disclosed and described. The present invention provides automatic fluid pressure operated means to open and close the workholding chuck, comprising a cylinder mounted on the axis of rotation of the chuck 20 and containing a rotating piston whose piston rod is the draw rod for the chuck. This constructional feature has greatly simplified the organization of the workhead.

Another object of the present invention 25 resides in the provision of fluid pressure operating mechanism to reposition the cross slide at the end of each grinding operation.

The invention further involves an important improvement in the McDonough system of caliperizing by a rotating gauge. In 30 the McDonough patent and other subsequent patents and applications, the gauge is moved against the workpiece at each reciprocation of the grinding wheel. This involves an unnecessary shock to the gauge and to the 35 workpiece. A very important object of the present invention involves the provision of means to hold the gauge from engaging the work-piece until a specified part of the grinding 40 operation is completed. This is made possible, in the illustrative embodiment of this phase of the invention, by using the position of the cross slide, that feeds the grinding wheel in relation to the workpiece, as an 45 auxiliary gauging means to determine when the rotating gauge shall be allowed to come up to the workpiece.

Further objects of the invention include 50 the synchronization of the various motions of the machine, and the organization of most of them into a complete fluid pressure operating system. It has been found most advantageous to perform periodic operations, of 55 which the present machine illustrates so many examples, by fluid pressure operating means. The coordination of the whole into a complete system with the smallest possible number of actuating valves is an important 60 object of the invention.

60 Further objects of the invention will be made apparent as the description proceeds.

In the drawings,

Fig. 1 is a front elevation of a grinding machine incorporating our invention.

Figs. 11 and 12 are front and rear elevations respectively, of the switch mechanism that is actuated by the rotating gauge, the 90 cover of the switch box being removed in Fig. 11.

Fig. 13 is a front elevation, with the cover partly broken away, of the cross slide operating mechanism for the wheelhead.

95 Fig. 14 is a vertical axial sectional view, taken on the line 14, 14 of Fig. 13.

Fig. 15 is a diagrammatic representation of the piping of the machine, showing the various valves and cylinders, however, in correct axial sectional representation.

100 Fig. 16 is a wiring diagram.

Fig. 17 is a view showing the dog-resetting member in relation to the sliding dog.

Like reference characters refer to like parts 105 throughout the drawings.

Referring to the drawings, particularly to Fig. 1, the machine provides the usual reciprocating table or carriage 1, which is ordinarily provided in any internal grinding 110 machine. In such a machine, either the grinding wheel or the work to be ground may be carried on the table 1, the reciprocation of the latter being utilized in either case to produce a relative traversing movement between the grinding wheel and the work. As here shown, the table 1 supports and carries a wheel head 2 of the usual construction,—while the work which is to be operated upon is held in a workhead 3, the latter being carried by a bridge 4 which spans the slideways provided by the machine frame for the back and forth movement of the table 1.

115 This back and forth movement of the table 1, to cause the grinding wheel 5, carried on the rotating spindle 6, to make the required interior traverse of the rotating workpiece, is imparted by fluid pressure controlling and reversing mechanism, which is not per se the subject of the present invention, but which is 120 125 130

disclosed in Patent No. 1,582,468 to Heald and Guild granted April 27, 1926. However, a brief description of such mechanism is necessary to a clear understanding of the present invention, and such will now be given.

The machine provides a cylinder 7 containing a double acting piston whose piston rod 8 is connected to the table 1 as shown in Fig. 1. The cylinder 7 is shown in Fig. 15. Referring to this figure, fluid under pressure is admitted to one end or the other of cylinder 7 from any source of supply, such as a pump 10, which communicates through valve means that will be described, with a supply line 11, which leads to a reversing valve 12 disposed in a suitably apertured casting 13 that is located on the front of the machine. The position of the valve 12 determines the flow of pressure medium to one end or the other of cylinder 7, by way of pipe 14 or pipe 15, as the case may be. The return of pressure medium from the reversing valve 12 is by way of a pipe 16, which leads to a pump supply chamber or tank, not herein illustrated.

The casing 13 provides a passage 18 to the reversing valve 12 from the fluid pressure supply pipe 11. The passage 18 is provided with a rotatable plug or throttle valve 19, adapted to be adjusted by a handle 20 (see Fig. 1) the position of which determines the quantity of pressure fluid flowing through the passage 18, and hence the speed at which the table 1 is reciprocated.

Pipes 14, 15 and 16 are connected to the reversing valve 12 by means of passages 21, 22 and 23, respectively. The valve 12 is adapted to be oscillated, and is so formed that it will connect passages 18 and 21 at the same time as it connects passages 22 and 23, this being the position of the valve in Fig. 1. In the other position of the valve 12, it connects the passages 22 and 18 together, also the passages 21 and 23. Thus, as will be readily apparent, one position of the valve 12 subjects the left hand side of the piston in cylinder 7 to the fluid pressure generated by the pump 10, while at the same time connecting the right hand side of the piston to the exhaust pipe 16, and the other position of the valve 12 reverses these conditions.

Thus the direction in which the table 1 moves is reversed every time the valve 12 is moved from one extreme position to the other extreme position, while it is apparent that if the valve is placed midway between its extreme positions, the piston will be urged neither to the left nor to the right. In order to control the oscillatory valve 12, it is fastened to a shaft, not shown, to which is secured a hand lever 24, Fig. 1. The hand lever 24 is connected by a pin and slot connection with a reversing lever 25 which is pivoted at 26 to the machine frame. The upper part 65 of the member 25 is adapted to be engaged

by spaced adjustable dogs 27 and 28 carried by the table 1.

Associated with the reversing lever 25 or the hand lever 24 is a suitable detent or snap-over mechanism, not shown, which may be of any suitable type, such as that shown, for example, in the aforesaid patent to Heald and Guild. It will thus be apparent, that if the prongs of the reversing member 25 are located so as to be struck alternately by the dog 27 and the dog 28, the carriage 1 will be reciprocated through a definite stroke.

The present machine makes use of the table stroke controlling dogs and associated mechanism described in the aforesaid patent, 80 Guild No. 1,682,672. The mechanism disclosed in the accompanying drawings for this purpose is the same as that shown in said Guild patent, with mere changes of form and shape, and hence will be very briefly described 85 herein. As shown in Fig. 1, the left hand table dog 27 is carried by a block 29 which is slidably mounted on the table 1, but normally maintained in spaced relation to a fixed block 30 by means of a latch device 31. The block 90 30, the same as the block 32 that carries dog 28, is adjustably fastened to the table 1 by means of thumb screws 33, 33 engaging a suitable screw rack 34.

Suitably mounted on the front of the machine, as in a box or casing 35, are a pair of electromagnets 36 and 37, the former only being visible in Fig. 1, because it completely hides the latter. Electromagnet 36 is provided with an armature 38 which forms one 100 arm of a three armed member pivoted at 39, whose upwardly extending arm 40 normally, during the working reciprocation of the grinding wheel 5 in the internal bore of a workpiece, lies adjacent the right hand end 105 of the latch member 31. The electromagnet 37, which may be seen in Fig. 16, is provided with an armature 41, to which is similarly attached an upwardly extending arm 42.

Energization of the electromagnet 36, with 110 consequent elevation of the lever arm 40, due to attraction of the armature 38, results in an amplification of the normal stroke of the table 1, by reason of the fact that the left hand table dog 27, after the latch member 115 31 is raised, does not swing over the reversing lever 25, but on the contrary is moved by the latter relative to the table 1. The outward stroke of the table, and consequently of the grinding wheel 5, continues until such time as the block 29 brings up against the firmly fastened block 30, whereupon the resistance afforded is sufficient to swing the reversing lever 25 to the opposite position, resulting in a reversal of the travel of the table. 120 The sliding block 29 is automatically returned to its original position with respect to the block 30, and with the latch 31 in engaged position, by means of a resetting member 43 which is resiliently urged into the path of 130

the lower end of the block 29 of a spring 44.

Energization of the electromagnet 37, resulting in attraction of the armature member 41 and the lifting of its attached lever arm 5 42, on the other hand, results in giving the table 1 a more extended stroke to the right. This action takes place by reason of the fact that the left hand table dog 27, instead of being firmly attached to its carrying block 10 as is the case with the right hand table dog 28, is pivotally mounted on its carrying block 29, normally resting by gravity in the position shown in Fig. 1. The lever arm 42 is in the same vertical plane as the right hand 15 prong of the reversing member 25 with which the dog 27 contacts, and consequently, when said lever arm 42 is raised, the dog 27 on the next right hand stroke of the table rides on the inclined surface provided by the lever 20 arm, clear of the reversing member 25, thus permitting the table 1 to continue its movement to the right without being influenced by the normal reversing mechanism.

The table 1, under these conditions, continues to the right well beyond the range of the limited dressing stroke heretofore described, and until such time as a third reversing dog 45 engages one or the other prongs of the reversing lever 25. The dog 45 is 30 formed on the end of a block 46 which provides a thumb screw nut 33 for adjustment along the table.

From the foregoing it will be seen, that during the preliminary or rough grinding operation, the table 1 automatically traverses back and forth over a limited although adjustable range; that thereafter the energization of the electromagnet 36 results in giving the table a limited stroke to the right, for 40 the purpose of dressing the grinding wheel 5, as will more fully appear hereinafter; and that finally the energization of the magnet 37, results in giving the table a still further stroke to the right, during which time the 45 ground workpiece is discharged from the machine, and an unground one placed in the work-holding chuck from a suitable magazine 47, the change being effected by means of a chute 48 and a transferring device 49, 50 the exact construction and mode of operation of which will not be herein described since such forms the subject matter of the copending application of Highberg above referred to. The foregoing machine motions, 55 and many others which will be hereinafter described, are inaugurated by the electromagnetic instrumentalities illustrated in Fig. 16.

As already stated, the machine of the invention is a completely automatic one, and 60 once it is properly set up for the grinding of a given size and style of workpiece, it will not stop until either the supply of workpieces has been exhausted, or the grinding wheel has been worn beyond a usable size.

65 Assuming, therefore, that the machine has

been provided with a fresh grinding wheel 5, the magazine 47 filled, all adjustments made, and the hand lever 24 shifted to the left to cause the wheel to start inward toward the workpiece, by movement of the table 1 to the left under the influence of the fluid pressure motor embodied in the piston and cylinder unit, the table so continues until the dog 27 lifts over the corresponding prong of the reversing lever 25, whereupon the table 1 and grinding wheel 5 continue to reciprocate, the latter in contact with a workpiece in the chuck of the machine. During this time the machine may be said to be under the control of the automatic reciprocating mechanism, and the grinding continues uninterrupted and unchanged until the first electric contact is made in response to movement of the cross slide of the machine. For a proper understanding of this mechanism, which next assumes control of the machine operation, it will be necessary to understand first the general construction of the cross feeding instrumentalities which feed the wheel and work together on a line transverse to the reciprocation of the table 1, and secondly the means for actuating this mechanism and these matters will now be described.

In internal grinding machines it has been common to cause this cross feed by movement of the workhead or movement of the grinding wheel head, and generally irrespective of whether the grinding wheel or the workhead undergoes the reciprocatory motion. In disclosing the cross feed of the present invention as embodied in movement of the workhead, therefore, it will be understood that the invention is not limited thereto.

Referring now to Fig. 3, a portion of the workhead 3 is shown, involving a rotatable spindle 50 suitably mounted in bearings 50a, Fig. 8, which is adapted to be connected to a pulley 51, as by means of a multiple disc clutch 52 only the outside of which is shown, 105 since it is of common construction. A belt 53 driven from any suitable source of power rotates the spindle 50 continuously except when the clutch 52 is moved to disengaged position by a mechanism which will be here- 110 after described.

The entire workhead 3 is pivotally mounted on a cross slide 54, as by means of a pivot post 55 and concentric pedestal 56, the former fitting in the pivot hole 57 provided by the workhead 3. In this manner the workhead can be adjusted angularly in relation to the axis of the wheel 5, in order to provide for the grinding of tapered bores in workpieces if desired.

The cross slide 54 is mounted in V-ways 58, 58 for movement transversely of the machine. Such movement is produced by the angular movement of a lever 59, which is pivoted at 60 to the bridge 4, and one end of which 120

is in contact with a depending lug 61 provided by the cross slide 54, while the other end thereof is in contact with a cam 62 which is rotated as will be hereinafter described. 5 Suitable hardened wearing plates or shoes 63 and 64 are provided by the lever 59 where it contacts the lug 61 and the cam 62, respectively.

The cam 62 provides a generally involute 10 peripheral surface, and by its intermittent revolution procures the cross feed between the grinding wheel and the workpiece, by movement of the slide 54. This inward feeding movement of the slide 54 is opposed by 15 springs 54a (see Fig. 4) arranged between said slide and the bridge 4; said feeding movement procures the compression of said springs. The mechanism to rotate the cam 62 is contained in a box-like structure 65 20 mounted on the front of the machine, preferably on the bridge 4, as shown in Fig. 1.

As shown in Fig. 6, the cam 62 is fastened to a shaft 66 that is suitably mounted in ball bearings 67, 67, provided by the casing 65. 25 A hand wheel 68a provides means for manually controlling the position of the cam. The cam is rotated by ratchet and pawl mechanisms, constituting a coarse feed pawl, a fine feed pawl, and means for adjusting the 30 stroke of each; this mechanism in its details being of the same general construction as shown in United States Letters Patent No. 1,673,078, granted June 12, 1928.

Describing this mechanism very briefly, 35 therefore, the ratchet wheel is shown at 68 and is fastened directly to the shaft 66. Pivotaly mounted on the said shaft 66 are respectively a two and a three armed member 69 and 70, the former providing an arm 71 upon which at 72 is pivotally mounted a pawl 73 that is urged into engagement with the ratchet 68 by means of a spring 74. The member 69 also provides a cam portion 75 40 and a stop arm 76.

The three armed member 70 provides an arm 77 upon which is pivotally mounted at 78 a pawl 79 that is also urged into engagement with the ratchet 68 by means of a spring 80. The three armed member 70 further 45 provides an arm 81 having a cam portion 82 and a stop arm 83.

Referring to the fluid pressure diagram of Fig. 15, it will be apparent that pipes 84 and 85 are shunted into the pipes 14 and 15, respectively, which supply fluid to the left hand and right hand ends of the cylinder 7. Consequently first the pipe 84 and subsequently the pipe 85 will receive fluid under pressure, which is conducted, respectively, to the left and right hand ends of a cylinder 86 mounted in or under the box 65. As the table 1 reciprocates back and forth, a piston 87 in the cylinder 86 will likewise reciprocate, and referring back again to Fig. 5, a lever 88 55 provides a downwardly extending arm ex-

tending into a slot 89 provided by the piston 87. The upper end of the lever 88 provides a roller 90 which is therefore oscillated back and forth, and in its path of oscillation lie the cam portions 75 and 82. 70

It will thus be seen that the members 69 and 70 are oscillated on the pivot consisting of the cam shaft 66, the amplitude of oscillation of each of said members 69 and 70 being determined by the shape of the cam surfaces 75 and 82 and by eccentric stops 91 and 92 which engage stop screws 93 and 94, respectively, provided by the arms 76 and 83. Springs 95 are employed to urge the arms 76 and 73 towards the eccentrics 91 and 92. 75 By means of levers 96 and 97, mounted on the front of the box 65, the positions of the eccentrics 91 and 92 can be adjusted, and consequently the amount of motion given to the pawls 73 and 79 can be adjusted, this mechanism being substantially the same as the structure disclosed in the patent to Kempston and Gallimore above referred to. 80

The pawl 79 is the coarse feed pawl, ordinarily moves a considerable number of the 90 ratchet teeth at a given stroke, depending upon the setting of the lever 97, and is actuated at both ends of the stroke of the table 1. This is due to the fact that the cam portion 82 is so shaped as to allow the oscillating roller 90 to pass beyond it at each oscillation. The pawl 73 is the fine feed pawl, ordinarily moves the ratchet through a distance of 1, 2, 3 or 4 teeth, and is moved only 95 at one end of the stroke of the table 1, viz. the left hand end. This is due to the fact that the cam portion 75 is so shaped that the oscillating roller 90 cannot pass beyond it at one end of its oscillation. Associated with the pawls 79 and 73 are electromagnets 100 and 101, respectively, adapted to successively remove the pawls from the ratchet wheel 68 thus to render ineffective their oscillations. The means for withdrawing the pawls by 100

energization of the electromagnets are the armature members 102 and 103 which are pivotally mounted in the box 65, and provide tail pieces 104 and 105 engaging rollers 106 and 107 provided by the pawls 79 and 73, substantially as described in the aforesaid patent to Kempston and Gallimore. When first 105 one and then the other pawl is withdrawn from the ratchet, it is held in the withdrawn position by latch means disclosed in the aforesaid patent and shown in dotted lines in Fig. 5 and in the isometric view of Fig. 7, a lever 108 being provided to manually release the latches, as described in the aforesaid patent. For the automatic operation of the machine, a solenoid 109 is provided which shifts a rod 110 to the left, this rod controlling the releasing means for both of the latches. 110

According to the present invention, the cross feeding mechanism just described provides means for putting out of action the 115 120 125 130

pawl 79 which procures the coarse cross feed. The cross feeding mechanism described further provides means for procuring the dressing of the grinding wheel 5, this being inaugurated by the energization of the electromagnet 36. To that end the ratchet wheel 68 has fastened thereto a cam 111 in the path of which is an adjustable screw 112, provided by an arm 113 pivoted at 114 in the box or 10 casing 65. The arm 113 provides a portion 115 extending at right angles to its main portion, providing a pair of contact points 116 and 117, only the first of which is shown in Fig. 5, since the second is hidden behind it. 15 In the path of movement of the points 116 and 117, which are illustrated diagrammatically in Fig. 16, is a pair of insulated terminals 118 and 119, respectively, which are carried by levers 120 and 121, respectively, whose 20 hub portions are mounted on a pivot stud 122 provided in the box 65. The positions of these levers can be readily adjusted by means of eccentric adjustment devices 123 and 124 controlled from dials 125, 126 on the front 25 of the box.

Referring now to Fig. 16, electric current may be supplied to the machine by any suitable means such as a generator 130. One terminal of this generator is grounded as at 30 131, while the other terminal connects to a lead 132 having many branches as shown. When, in consequence of the movement of the cam 111, contacts 117 and 119 come together, these contacts being adjusted to come together before the contacts 116 and 118, an electric circuit is completed, which energizes the magnet 100 in the following manner:—

The current flows from the generator 130 through the conductor 132, through a branch 35 lead 133 to a switch bar 134. The switch bar 134 is one of a pair of such bars, so located as to be engaged by a movable bar 135, provided by an oscillatory switch member 136, which is oscillated in a manner fully described in the 40 aforesaid patent to Guild. It will be noted that at this stage in the grinding operation, and until after the automatic dressing, the switch member 136 is in the position shown in Fig. 16, with the bar 135 engaging the 45 stationary bar 134.

Movable bar 135 is connected to a lead or conductor 137 which leads to one terminal of the magnet 100. The other terminal of the magnet 100 is connected by means of a conductor 138 to the contact 119, and since this 55 contact 119 is at that time in engagement with the contact 117, which is grounded at 139, the circuit is completed, and the electromagnet 100 is energized.

60 This causes the coarse feed pawl 79 to be withdrawn from the ratchet wheel 68, and consequently the grinding proceeds with a fine cross feed, thereby procuring a gradual reduction in the spring or deflection of the 65 wheel spindle 6.

Further feeding of the ratchet wheel 68, under the continued actuation of the fine feed pawl 73, moves the cam 111 and causes further lifting of the contact arm 113. This, after a definite number of reciprocations of the grinding wheel 5, causes the contacts 116 and 118 to come together, and thus energizes electromagnet 36 in the following manner:—

Conductor 132, which has already been described leads from one terminal of the generator 130, connects to a branch lead 140 which connects to one terminal of the electromagnet 36. The other terminal of the electromagnet 36 connects by means of a lead 141 to a stationary contact bar 142, which is at that time engaged by a movable contact bar 143 carried by the oscillatory member 136. The contact bar or plate 143 connects by means of a conductor 144 with the terminal 118, and thus without further description, it will be apparent that the electromagnet 36 is energized at this juncture.

It has already been described how energization of the electromagnet 36, resulting in the raising of the lever arm 40, procures the withdrawal of the grinding wheel 5 from the workpiece. Simultaneously with this action a dressing device or diamond 145 is lowered into the path of travel of the wheel 5, thus dressing and truing it by predetermined amount. The diamond 145 is mounted in a suitable plug or nib which is carried by an oscillatory member 146 that is mounted on the machine frame in a manner fully set forth in a patent to Guild and Grimshaw No. 1,655,903, granted Jan. 10, 1928. It is unnecessary, therefore, to describe the details of the mounting of the diamond in this present specification, except to note that said diamond is lowered by the rearward movement 105 of a lever 147 which draws rearwardly a link 148, said lever being fastened to a shaft 149 and operated in a manner which will now be described.

Referring to Fig. 15, a branch pipe 150 shunted into the fluid supply pipe 11 leads fluid to an entrance port 151 of a valve generally designated by the numeral 152. In the normal position of the valve member 153 in this valve, the port 151 is kept covered. Referring to Fig. 1, attached to the armature 38 and arm 40 is a third arm 154, which is connected to the valve 153, so that when the electromagnet 36 is energized, the valve member 153 is drawn to the right, Figs. 1 and 15, and fluid is admitted to a port 155 and thence into a cylinder 156 by way of piping 157.

This cylinder 156 is suitably formed in the stand or pedestal upon which the diamond operating and adjusting mechanism is mounted, which is indicated at 158 in Fig. 1. In the cylinder 156 is a piston 159, which, when the fluid is admitted thereto, is driven rearwardly of the machine. A lug 160 on the end 130

of the piston 159 is in engagement with a portion of the lever 147, and consequently rocks it rearwardly.

When, as already described, the grinding wheel 5 is returned into the workpiece subsequent to the dressing operation, the diamond 145, by movement of the table 1, is returned into its original position as shown in Fig. 2. This is effected mechanically by means of a cam bar 162 adjustably mounted on the rear of the machine, as shown in Fig. 2, said cam bar striking a roller, not shown, that is provided by a forwardly extending arm of the bell crank lever 147. This action, 10 of course, drives the piston 159 into the cylinder 156 again, and consequently forces the fluid out of said cylinder. The valve 153 has, by this time, been returned to the position shown in Fig. 15, and consequently the 15 fluid is exhausted through a port 163 which communicates with a supply tank, or other source of fluid pressure. The manner in which the valve 153 is returned to its initial position is described somewhat more at 20 length in the patent to Guild No. 1,682,672 above referred to; suffice it to say herein that said return is effected by engagement of a cam surface 164 provided by the sliding block 29 with a latch portion 165 on the lever 40. 25 The rocking of the shaft 149 in order to place the dressing device 145 in dressing position, and subsequently remove it from the path of the grinding wheel 5 is made use of, first to slow down the reciprocatory traverse 30 of the table 1, so that the dressing of the wheel 5 will take place at a slow linear speed in order that no high spots may be left in the wheel, and second to cause the reciprocatory traverse of the table 1 during the final and 35 finishing cuts, subsequent to the dressing operation, to be taken at any predetermined speed of traverse intermediate the dressing speed and the preliminary or roughing speed, inclusive of both of them. To that end, an 40 arm 166, only the hub of which is shown in Fig. 2, is suitably fastened to the shaft 149, and to the inner end of the arm 166 is attached a link rod 167. The rocking motion of the shaft 149 to lower the diamond 145 consequently involves a raising of the link 167. 45 At the lower end of the rod 167 are a pair of adjustable nuts 168 and 169 in between which is located one arm 170 of a bell crank lever 171. The upper end of the latter is connected 50 to the outer end of a valve member 172, which is shown in section in Fig. 15. The valve member 172 is contained in a casing 173 and provides an entrance port 174 connected by means of pipe 175 with the pump 10. The entrance port 174 is in communication with a hole 176 through a sleeve 177 by means of which the fluid is at all times admitted to the central space in the valve between adjacent enlarged cylindrical portions 178 and 60 179. This central space communicates with

a chamber 180 which communicates, through a gap left between the sleeve 177 and another sleeve 181, with the fluid pressure pipe 11, which admits fluid to the main reversing valve that controls the reciprocation of the table 1. When, therefore, the valve member 172 is moved to the right, Fig. 15, as already described, the cylindrical portion 178 thereof covers part at least of a circular orifice extending between sleeves 177 and 181, and which is in effect a port 182, and thus acts as an independent throttle to automatically lower the speed of travel of the table 1 for the dressing operation. 70

The movement of the valve member 172 to the right has a further important function in allowing the gauge of the machine to gauge the work from that time to the finish of the grinding operation, but before describing this, the construction and general operation 80 of the parts in the workhead will be set forth.

Referring to Figs. 3 and 8, the chuck spindle 50 is hollow, and inside of which is a tubular draw rod 183 the longitudinal movement of which causes the chuck 184 to grip or release a workpiece. The draw rod 183 revolves by reason of the fact that it is frictionally connected to a spider 185 which in turn is attached as by screws 186 to the body 187 of the chuck, the latter being revolved by 90 reason of the fact that it is directly attached to the rotating chuck spindle 50. 95

Within the draw rod 183 is a third hollow rod, viz. the gauge rod 190. This rod is also revolved, by reason of a spline connection 191 with the draw rod 183. It will thus be seen that the three rods or tubes 50, 183, and 190, revolve simultaneously about a common axis, the first being held from longitudinal movement in bearings 50^a, but the last two being 100 independently longitudinally movable inside of said tube 50. 105

The gauge rod 190 provides a screw threaded portion 192 and a plain portion 193, both of which extend rearwardly beyond the draw rod 183. A tubular member 194 is in screw threaded engagement with the threads 192 and firmly attached thereto by means of a check nut 195. This tubular member 194 provides a stuffing box 196 which forms a 110 water-tight connection between the said tubular member and the gauge rod. 115

The tubular member 194 provides a shoulder 197 and screw threads 198 on which is a nut 199. By means of the nut and the shoulder, the inner race 200 of a ball bearing 201 is firmly fastened to this tubular member 194. 120

It will be seen that the tubular member revolves with the gauge rod 190. A non-rotatable pipe 202 provides a portion 203 extending into the tubular member 194, and having a flange 204 in a stuffing box 205 provided therein. The non-rotatable pipe is held in place by means of a sleeve 206 and a flanged nut 207, which compress the stuffing 125 130

box onto the flange 204. This pipe 202 has a flexible connection 202^a with the usual water pump, not shown, provided by or associated with all grinding machines of this class, 5 by means of which water or other suitable coolant is admitted into the sleeve 194 and thus into the rotating gauge rod 190, through which it is carried directly to the workpiece in the chuck. The rod 190 thus serves as a 10 coolant conveying pipe as well as a gauge rod.

Still referring to Fig. 8, the workhead 3 provides, on the under part thereof which overhangs the left hand end of the machine, 15 a double pair of alined bearing portions 208, 208. These bearing portions 208 slidably receive two rods 209. Referring now to Fig. 10, the rods 209 are suitably fastened as by means of nuts 210 to a plate 211 which provides a semi-circular yoke 212 supporting the outer race of the ball bearing 201. The plate 211 further supports a member 213, suitably fastened to it as by screws 214, which provides an upwardly extending split 25 portion 215 that surrounds the pipe 202 and may be suitably clamped on said pipe as by means of a screw 216. Thus it will be seen that rearward movement of the rods 209 and consequently the plate 211 will result in 30 rearward movement of the gauge rod 190.

By means of a spring 217, which is attached to a stationary post 218 at one end and to a pin 219 adjustably fastened by means of a nut 220 to the plate 211 at the 35 other end, these parts are urged to the right, Fig. 8, to carry the gauge 221 into engagement with the bore in the workpiece α . The parts are shown in this gauging position in Fig. 8. Of course the gauge 221 can not enter the workpiece until the workpiece is 40 ground to the correct size, and inasmuch as the grinding wheel 5, in its traversing movement to grind the workpiece, must pass completely through the latter, the gauge must 45 be out of the way of the grinding wheel on the extreme left hand stroke of the latter. Consequently means is provided to shift the gauge rod forcibly to the left at every reciprocation of the table.

50 As shown in Figs. 8 and 9, a triangular bracket 222 is mounted on the rods 209 and suitably fastened thereto. This bracket adjustably supports a bolt 223 which is secured in any suitable position by adjustment of a 55 nut 224. The end of this bolt is in the path of travel of the table 1, and consequently the movement of the table periodically shifts the whole mechanism to the left.

The periodic shifting of the gauge rod and 60 gauge by movement of the grinding machine table or carriage is not the subject matter of the present invention, being shown in a patent to Conradson, et al., No. 1,534,302. According to said Conradson, et al. patent and 65 also the aforesaid McDonough reissue pat-

ent, the gauge is continually urged by a spring towards the workpiece, and only prevented from entering the workpiece by the size of the hole. The continual reciprocation of the gauges in the manner described 70 results in a hammering action which gradually wears them down, and necessitates their frequent inspection (a great number of different size gauges being, of course, carried in stock) to see that they are of the correct size. 75 The present invention, therefore, provides a distinct improvement over the prior patented constructions, in providing means for holding the gauge rod 190 and gauge 221 and associated parts to the left until such time as 80 the preliminary grinding of each workpiece is completed. In other words, the machine of the present invention provides automatic workpiece measuring means of one type, to determine when the automatic workpiece 85 measuring means of the reciprocating and rotating gauge type shall come into operation, thus relieving the latter from the onerous and unnecessary part of the work, and bringing it into operation only to secure that 90 final degree of accuracy which is beyond the capabilities of the other measuring means. This mechanism will now be described.

Still referring to Fig. 8, a cylinder 225 is suitably formed in the workhead 3 or a casting 226 attached to it. In this cylinder 225 is a piston 227 having a piston rod 228. The rod 228 extends through an end wall 229 that forms the boundary of the cylinder 225, and is in abutting engagement with the right 100 hand portion of the plate 211.

Opening into the right hand side of the cylinder 225 is a port 230 and normally, during the preliminary grinding operation and before the dressing contacts 116 and 118 105 are brought together, fluid under pressure is admitted to the cylinder 225 through the port 230, and thus the piston rod 228 is held to the left to its fullest extent, thus holding the gauge 221 and all associated parts to the left 110 where it is impossible for the gauge to touch the workpiece.

Referring back, therefore, to Fig. 15, in which the piston and cylinder parts are shown in somewhat diagrammatic form, it 115 will be seen that the port 230 is in communication by means of a pipe 231 with a port 232 through the sleeve 177, which communicates with the interior portion of the valve 172 between the enlarged portion 179 120 and enlarged portion 233 at the right hand end of the valve member. This interior portion 234 of the valve is in communication through a port 235 with the entrance port 174 for the fluid, and thus in the normal position of the valve 172, the fluid is active 125 against the end of the cylinder 227 as aforesaid. When, however, the valve member 172 is moved to the right, which takes place in response to energization of magnet 36, the 127

enlarged portion 179 of said valve member covers the port 235, while the enlarged portion 233 uncovers a port 236 leading back to the pump supply chamber. This immediately 5 relieves the pressure on the piston 227 and the latter, owing to the influence of spring 217, is forced into the cylinder, and the gauge 221 and all associated parts are free to move to the right, obstructed only by the periodic 10 movement of the table 1 and the workpiece itself.

In the description of the machine as a whole, it will now be seen that the grinding has proceeded to a point where the rough 15 grinding has been finished, and the cross feed slowed down to a point where the side pressure on the spindle 6 has been relieved. The stroke of the table 1 was then extended, and the wheel 5 subjected to a dressing operation by passing it twice in front of a diamond 145 and in engagement therewith. This operation, as will be remembered, took place at a slower speed of movement of the 20 table 1 than the normal movement, owing to the movement of the valve 172 by means of the link 167 operated from the oscillating shaft 149. At least, since the valve 178 and 25 19 are in series, it can be said that the dressing operation will take place at a low speed 30 whatever the adjustment of the valve 19.

The sliding block 29, is then restored to its original position on table 1 as already set forth and the wheel 5 returns to the workpiece. This is accompanied by a return oscillation of the shaft 149 and the return of 35 the dressing point 145 to the position shown in Fig. 2. This return oscillation of the shaft 149 does not completely reset the valve 172, since there is a lost motion between the nuts 40 168, 169, on the rod 167 and the portion 170 of the bell crank lever 171 that is located between them. Thus the enlarged portion 179, while it moves somewhat to the left in response to the return of the grinding wheel 5 45 into the workpiece, does not uncover the port 235 again during the grinding of this particular workpiece, or at least the nuts 168, 169 can be set so that it will not, and they are intended to be so set, in order that the gauge 50 221 may from this time forth take control of the machine and bring the grinding operation to a termination when the workpiece has been ground to the correct size.

It has just been stated that the machine is 55 now under the control of the gauge 221. As the machine was previously under the control of the cross slide operating mechanism and electric contacts operated thereby, it will be apparent that provision must be made to 60 transfer this control. To that end, the carrying block 30 provides a pair of downwardly hanging arms 238 and 239 which are pivotally mounted on said block and capable of being lifted from the position shown in 65 Fig. 1 although not capable of being de-

pressed from said position. In the path of the arm 238 is an upwardly extending arm 240 of the switch member 136, while in the path of the depending arm 239 is an arm 241 of said switch member. The location of the 70 oscillatory switch member 136 on the machine is such that with the switch in the position shown in Fig. 1, the movement of the table 1 to carry the wheel 5 into the workpiece at the commencement of the grinding operation moves said oscillatory member 75 to the position shown in Fig. 16, with the pair of plates 135 and 143 in engagement with stationary bars or plates 134 and 142, while movement of the table outward to perform the dressing operation, as already described, moves the switch 136 back again to the position shown in Fig. 1, where it remains until the commencement of a subsequent grinding operation. Thus it will be 80 seen, that by the dressing stroke aforesaid, the circuits through magnets 36 and 100 are definitely broken, thus preventing any further dressing operation despite the maintenance of engagement between the contacts 85 116 and 118, and 117 and 119, respectively. The pawl 79 is not, however, allowed to contact the ratchet wheel 68 again, owing to the beforementioned latching mechanism of 90 Kempton and Gallimore Patent No. 1,673, 95 078.

Referring now to Figs. 10 and 12, a boss 242 is provided by the plate 211, and a rod 243 extends through this boss 242, being suitably fastened thereto in any adjusted position, as by means of a screw threaded portion 244 which engages threads inside the boss, and is locked in position by means of a check nut 245, both the check nut and the head of the rod having knurled thumb 100 portions as shown.

Referring now to Figs. 1, 11 and 12, it will be seen that a box or casing 246 is suitable attached to the workhead as to the casting 226 provided thereby. The rod 243 extends into 105 this casing but normally is not in engagement with a tail piece 247 provided by a latch member 248. The latch member 248 is urged downwardly by means of a spring 249, and during the grinding operation holds a contact member 250, which carries a contact point 251, in open circuit position. The parts are shown in this position in Fig. 16. The contact member 250 is secured to a shaft 252 which is suitably journalled in the box 246, 110 and therefore, the contact member 250 may be said to be pivotally mounted in the box; a spring 253 is effective thereon to carry the contact terminal 251 into engagement with a contact 254 provided by the casing 246. 115

Subsequent to the dressing operation, the grinding operation proceeds with the fine feed pawl 73 gradually causing the grinding wheel to enlarge the workpiece bore, the rotating gauge 221 being urged against the 120 125 130

workpiece by the spring 217, except at such time as the end of the table 1 is actually in contact with the bolt 223, which occurs only at the extreme limit of the left hand stroke 5 of the table. When the workpiece α has finally been enlarged to the predetermined size, the gauge 221 enters said workpiece owing to the influence of the spring 217, and then the gauge rod 190, sleeve 194, pipe 202, bracket 215, plate 211, rods 209 and all associated parts are moved to the right. Since the rod 243 is attached to the plate 211 said rod is moved to the right, Fig. 11, and the end of the rod engages a tail piece 247 of the latch 248, thus lifting the latch from the tail piece of the contact member 250, allowing the terminal 251 to engage the terminal 254 under the influence of the spring 253. This completes an electric circuit as follows:—

Referring now to Fig. 16, a branch lead 255 from the main conductor 132 carries current to one terminal of the electromagnet 37. The other terminal of the electromagnet 37 is connected by means of a conductor 256 to the stationary contact terminal 254. Since the movable contact terminal 251 is grounded through the lever 250, as shown at 257, the circuit is completed and magnet 37 is energized. This causes the lever arm 42 to be raised into the path of the table dog 27, and procures an extended movement of the table 1 to the right resulting in carrying the grinding wheel 5 out of the workpiece. 35 The bringing together of contacts 251 and 254 results also in withdrawal of the fine feed pawl 73 from the ratchet wheel 68. As shown in Fig. 16, another branch lead 258 from the main conductor 132 carries current to the electromagnet 101, the other terminal of the electromagnet being connected by a conductor 259 to the terminal 254. It will thus be seen that the magnet 101 is energized coincidently with the magnet 37, and the fine feed pawl 73 is withdrawn from the ratchet wheel 68, and held in such a position by the latch means already mentioned. Thus at this time both pawls 79 and 73 are held away from the ratchet 68, which is consequently free to be 40 turned in a retrograde direction in order to prepare the machine for the grinding of a fresh workpiece. This retrograde motion of the ratchet 68, involving the turning back of the cam 62 to reposition the cross slide 54, takes place in the following manner:—

As shown in Fig. 16, a third arm 260 is associated with the arms 41 and 42 of the three armed member pivotally mounted on the stud 39 and associated with the rear electromagnet 37. The lower end of the arm 260 is connected to a valve member 261 which is located in the valve casing 262 that may be and preferably is an exact duplicate of the valve 152. When the valve member 261 is 45 moved to the right by reason of the energiza-

tion of the magnet 37, fluid is allowed to enter through a port 263 and ultimately conducted by a port 264, pipe 265 and a port 266 to a cylinder 267 in which is a piston 268. The cylinder 267, as shown in Fig. 5, is located 70 in the casing 65 on the front of the machine, and is connected at 269 to a lever 270 that is pivotally mounted at 271 and provides a segment rack 272 at its upper end. The segment rack 272, as shown in Figs. 5 and 6, is in engagement with a gear 273 fastened to the cam shaft 66, and consequently movement to the right of the segment 272 results in a counterclockwise movement of the cam 62 to bring the portion of its involute surface of small radius into contact with the shoe 64 on the lever 69. This permits the springs 54a to reposition the cross slide 54, so as to allow the grinding wheel 5 to enter a fresh workpiece which will be placed in the chuck by 80 the loading device 49. 85

The outward movement of the table 1 causes the transferring device 49 to remove the ground workpiece from the chuck, and to place a new workpiece, taken from the magazine 48, into said chuck. The movement of the transfer mechanism 49 and the manner in which it operates, will not be described herein in detail, since it forms no part of the present invention and is described and claimed in the aforesaid copending application of Highberg above referred to. A brief mention of this function, however, serves to point utility to the following further functions which the outer movement of the table 90 1 produces. Said movement of separation causes, first the stoppage of the chuck spindle 50, and immediately thereafter the movement of the draw rod 183 to the right, thereby opening the chuck for the discharge of a 95 ground workpiece and subsequent disposal 100 therein of an unground workpiece. 105

To that end a cam 274, adjustably mounted on the rear of the table 1, provides a pair of surfaces 275 and 276 which are adapted, by 110 movement of the table, to be successively brought into engagement with a roller 277 provided by a bell crank lever 278. The bell crank lever 278 is pivotally mounted at 279, and normally urged in clockwise direction by 115 a strong coil spring 280. The lower end of the bell crank lever 278 is connected to a sliding valve member 281, located in a valve 282, the internal construction of which is illustrated in Fig. 15. 120

As shown in Fig. 15, the valve member 281 provides two reduced portions 283 and 284 bounded by portions of full diameter 285, 286 and 287. Normally, before the table runs out as heretofore described, the reduced portion 125 283 keeps in communication a port 288 and a port 289, the former receiving a supply of pressure fluid by way of a pipe 290 from a port 291, opposite the main fluid port 174 and always in communication with it, while the 130

latter connects by way of a pipe 292 with a port 293 provided on the forward or right side of a piston 294, located in a cylinder 295 that surrounds the draw bar 183. (It should be observed that the cylinder 295 is seen in

Fig. 8 as from the front of the machine, and in Fig. 15 as from the back. We shall hereinafter treat this cylinder as though it were viewed from the front.)

10 Before describing the action of the piston and cylinder unit 294, 295, the other fluid connections of the valve 282 will be set forth.

Prior to the movement of withdrawal of the table 1, the valve member 281, besides 15 maintaining the ports 288 and 289 in direct connection, maintains a pair of ports 296 and 297 in connection with an exhaust port 298, this connection being established by the reduced portion 284. The port 296 communicates by way of a pipe 299 with a cylinder 300, having a piston 301 whose movement actuates the clutch for the work spindle. The port 297 communicates by way of a pipe 302 with a port 303 opening on the right hand 20 side of the piston 294. Prior to movement of the bell crank 278 by the cam bar 274, therefore, the cylinder 300 is opened to the exhaust while the pressure of the fluid is maintained on the left hand end of the piston 294. Thus the piston 301 in the cylinder 300 is in its lowermost position, and the clutch 52 is in its engaged position. Also the piston 294 is in its right hand position which causes the clutch fingers to firmly grip a workpiece.

25 At this point the novelty of the present construction of fluid pressure means for operating the chuck should be noted. The piston 294 is fastened, by means of a screw 304 directly to the chuck draw bar 183 which, as it will be remembered, rotates with rotation 30 of the chuck spindle 50. Thus the piston 294 rotates within the cylinder 295, and consequently no mechanical connections to transfer rectilinear movement to a rotating part 45 are needed in the present machine, since the piston 294 is moved by the pressure of the fluid. The piston 294 rotates without excessive friction in cylinder 295 by reason of the fact that the fluid used to produce the pressure is oil which, of course, is a lubricant.

Referring again to Fig. 15, and assuming that the cam surface 275 has engaged the roller 277 by reason of the movement of the table 1, thus moving the bell crank 278 (Fig. 50 2) the motion imparted to the valve 285 will be just sufficient to carry the portion 286 to the right of the port 296. This will admit the fluid from the entrance port 288 to the port 296, and will result in the raising of the piston 301 in the cylinder 300. The piston 301 is shown in Fig. 2, and in engagement with its upper surface is a roller 305 provided by a lever 306. The lever 306 is keyed to a shaft 307 which is shown in Fig. 2 and also in Fig. 3, and to this shaft 307 is keyed a yoke

308 which controls the disc clutch 52. Upward movement of the piston 301, therefore, results in disconnecting the clutch 52, and the chuck spindle 50, and all associated parts come to a stop.

Further rearward movement of the table 1 brings it to the position shown in Fig. 2 in which the cam surface 276 is in engagement with the roller 277. This results in further movement of the valve member 285 to the right, carrying the portion 286 thereof just beyond the port 297, but not so far as to cover the port 298. In this position of the parts, the valve port 297, as well as the port 296, is connected to the entrance port 288 and this admits fluid to the pipe 302 and to the right hand end of the cylinder 295. This forces the piston 294 to the right (Fig. 8) which pushes the rod 183 with it, and thus opens the chuck fingers for the discharge of the ground workpiece and the reception of a new one, fluid exhausting from the right hand end of the cylinder 295 in the following manner:

The pipe 292, it will be remembered, having a port 289 in the valve 282 leads to the right hand end of the cylinder 295 (or the left as viewed in Fig. 15). With the valve in the furthest extreme right hand position described, an annular chamber 309, which communicates through holes 310 with an axial passage 311 provided in the valve member 281, is over the port 289, and thus the fluid can exhaust to the interior passage 311. The passage 311 is in communication at that time by way of holes 312 with the right hand recessed portion 284 which covers the exhaust port 298.

Movement to the right of the valve member 285 just described, which admits fluid to the pipe 299, necessarily also results in the admission of fluid under pressure into a pipe 313 that is shunted into said pipe 299. The pipe 313 communicates with an entrance port 314 of a chamber 315 provided on the left hand end of the valve casing 173. The left hand end of the chamber 315 is bounded by a cylindrical portion 316 of the valve member 172 which has a substantially larger area than the cylindrical portion 178 of said valve member. Entrance of the fluid into this chamber, therefore, shifts the whole valve member 172 to the left into its original position as shown in Fig. 15, preparing the machine for a new grinding operation at the highest adjusted speed of table travel, as determined by the setting of the throttle valve 19.

The outward travel of the table 1 procures also the release of the pawls 73 and 79 from the latching mechanism described in the aforesaid patent to Kempton and Gallimore No. 1,673,978.

Referring now to Figs. 1, 5 and 15, a cam bar 317 is carried by the table 1, preferably by the sliding block 29. This cam bar, when

the table runs out beyond the dressing position, is adapted to engage a roller 318 on the end of an arm 319 pivoted to the machine frame at 320. Referring now to Fig. 16, a contact member 321 is carried by the arm 319, and adapted upon depression of said arm to engage a stationary contact 322. The latter is grounded as shown at 323, and since the contact 321 is connected by a conductor 324 to one terminal of a solenoid 109, and since the other terminal of said solenoid is reached by the conductor 132, the solenoid, at this stage in the operation of the machine, is energized.

The solenoid 109 has inside thereof a core 326, which is mounted on the rod 110 that connects the separate latch means of the aforesaid invention. Energization of the solenoid 109 causes the core 326, and consequently the rod 110, to be moved to the left, and this pulls a pair of arms 327 and 328 to the left, thus rocking a pair of shafts 329 and 330, and withdrawing the latches 331 and 332 from the tail pieces of armatures 102 and 103, and thus removing the guards 104 and 105 from the pins 106 and 107 and allowing the pawls 73 and 79 to reengage the ratchet 68, under the influence of springs 74 and 80.

The motion of the table 1 is ultimately reversed by means of the reversing dog 45, which as previously described engages the reversing member 25. This dog 45, before it contacts with the reversing member, engages the upper inclined surface of the lever 42, and thus rocks the three armed member comprising said lever 42, the armature 41, and the arm 260 in a clockwise direction to its original position, resetting the valve member 261, and opening the port 266 of the cylinder 267 through pipe 265 to an exhaust port 333 provided in the valve 262. Thereupon the ratchet 68 is free to be moved by the pawls in the grinding of the next workpiece.

Substantially coincident with this reversing action, the grinding wheel 5 is moved transversely of the machine, in order to compensate for the previous dressing of said wheel and to provide a surface to contact the dressing diamond 145 during the grinding of the next workpiece. To that end the wheel-head 2, as shown in Fig. 2, is mounted on a cross slide 334 which is in turn mounted on ways 335 provided by the table 1.

Referring to Figs. 13 and 14, the position of the cross slide 334 is adjustable by means of a screw shaft 336 upon the front end of which is mounted a hand wheel 337. In this manner the machine may be adjusted to grind different sized workpieces. Outward movement of the table 1 procures a slight angular turning of this screw shaft 336, to compensate for the reduction of the wheel 5 by wear and dressing in the following manner:

As shown in the aforesaid figures, a ratchet wheel 338 is fastened to the shaft 336, and

this ratchet wheel is adapted to be moved by a pawl 339 pivotally mounted at 340 on an arm 341. The arm 341 is journaled at 342 to a sleeve 343 surrounding the shaft 336, and is normally held in its lowermost position by means of a spring 344. When the table moves to the extreme right hand position, a cam 345 attached to a rod 346 on the front of the machine engages a roller 347 mounted on the arm 341, and rocks the said arm upwardly. This forces the pawl 339 into engagement with a wedge member 348 which causes the pawl to engage the ratchet wheel and move it. The number of teeth through which the pawl moves the ratchet wheel is adjustable by means of an adjusting device 349 engaging one end of a bell crank lever 350 pivotally mounted at 351, and to which said member 348 is fastened, a spring 352 holding the bell crank lever in its position of adjustment.

It will be apparent that any other suitable mechanism for advancing the position of the cross slide 334 at the end of each grinding operation would suffice so far as the present invention is concerned. In order that the operator may have a guide as to when to stop the automatic operation of the machine by reason of the reduction of the wheel 5 beyond efficient grinding diameter, a pointer 353 and a scale 354 are provided.

The return motion of the table 1, to carry the grinding wheel 5 back again into the workpiece is accomplished by the removal of the cam bar 274 from the roller 277 on the end of the bell crank lever 278. The spring 280 then moves said lever in a clockwise direction, and this causes the valve member 285 to be drawn to the left to the position shown in Fig. 15. Without further description, it will be apparent that this action causes the fluid pressure to be made active again on the left hand side of the piston 294, thus causing the chuck jaws to grip the fresh workpiece presented to it by the loading device 49, and likewise opening the cylinder 300 to the exhaust port 298, thus causing the springs, not shown, in the clutch 52 to move it to engaged position. The new workpiece is now in the chuck and is rotated therein and is ready for the entrance of the grinding wheel 5.

The resetting of the valve member 172, by reason of the entrance of the fluid into the chamber 315 as already described opens again the port 285 and admits the fluid under pressure to the cylinder 225, thus forcing the piston 227 to the left. This draws the gauge rod 190 and the gauge 221 away from the workpiece, allowing the grinding wheel to enter without interference by the gauge, and preventing the gauge from hammering the workpiece during the preliminary grinding. This action also, since it results in movement of the plate 211 to the right, Fig. 12,

causes the back side 355 of an adjustable bolt 356 to engage a lever 357 fastened to the shaft 252 upon which the contact member 250 is mounted, and thus causes the latch 248 to hold said member 250 in open circuit position until such time, at the end of the grinding of this next workpiece, as the gauge 221 enters the bore thereof.

A brief resumé of the cycle of operation of the machine will now be given for a clearer understanding of the invention. Assuming the machine to be in the position shown in Fig. 1, the magazine 47 loaded, and all adjustments made, with the hand lever 24 and the reversing lever 25 in middle or neutral position, the operator starts the machine in operation by shifting the hand lever 24 to the left, thus swinging the reversing lever 25 to the right and causing the table 1 to move to the left under the influence of the fluid under pressure which is admitted at that time to the right hand side of the cylinder 7 through the pipe 15. This movement of the table to the left causes the transferring device 49 to move rapidly toward the chuck, passing through a pair of jaws 359 which resiliently hold a single workpiece, and placing said workpiece between the chuck jaws. The moment the workpiece is in position between the chuck jaws, the roller 277 carried by the arm 278 drops from the cam surface 276 to the cam surface 275, and this results in a slight leftward movement of the valve member 285, which is sufficient, however, to cause the large portion 286 of the valve 287 to move to the left of port 297, thus connecting said port to the exhaust port 298. This connects the left hand side (Fig. 8) of the piston 294 to the exhaust, through pipe 302. The same movement moves the enlarged portion 285 of this valve member just to the left of port 289, and consequently connects port 289 with the supply port 288. This results in admitting fluid to the pipe 292, and thus to the right hand side of the piston 294 in the cylinder 295.

Since the piston 294 is at this time in its right hand position when viewed from the front of the machine, in which it holds the draw rod 183 to the right thus holding the chuck jaws 360 open, the resulting left hand movement of the piston 294 moves the draw rod 183 to the left and closes the jaws 360 on the workpiece.

The moment the jaws have closed, the transferring device 49 moves away from the workpiece and out of the way of the on-coming grinding wheel 5, this movement being effected in a manner which is no part of the present invention.

Further movement of the table 1 to the left, as it is viewed on the front of the machine, carries the roller 277 along the cam portion 275, and finally off the end of said cam portion. This results in giving the

valve member 285 a further movement to the left, Figs. 2 and 15, which both illustrate this valve as viewed from the rear of the machine. This movement disconnects the port 296 from the fluid pressure port 288, and reconnects it to the exhaust port 298, thus allowing the fluid to exhaust from the cylinder 300, and allowing the piston 301 to move down under the influence of the springs, not shown, in the clutch 52. Thus the chuck and all associated parts are rotated, to rotate the workpiece for the grinding operation thereon.

The grinding wheel 5 now enters the work-piece, the pivotally mounted dog 27 lifting over one prong of the reversing member 25. Just before the grinding wheel 5 enters the workpiece, the left hand arm 239 strikes the arm 241 of the switch member 136, and places said switch in the position shown in Fig. 16.

The grinding operation now proceeds, the table 1 traversing back and forth through a small adjustable range, and the pawls 73 and 79 reciprocating, owing to the admission of fluid through the pipes 84 and 85 into the cylinder 86. The pawl 73 undergoes a mere idle movement, because the pawl 79 moves so much further and causes rotation of the ratchet wheel 68 and an intermittent revolution of the involute cam 62. This gradually moves the lever 59, and shifts the cross slide 54 on the ways 58, thus moving the work-piece deeper and deeper into engagement with the grinding wheel 5. This action takes place without change until such time as, by the gradual movement of the ratchet wheel 68, the cam 111 engages the adjustable screw 112 and moves the arm 113 so far as to carry the contact 117 into engagement with the contact terminal 119. This causes energization of the electromagnet 100, which puts out of action the cross feed pawl 79, and allows the pressure on the wheel spindle 6 to gradually subside.

A predetermined but adjustable number of reciprocations of the grinding wheel 5 after this point, the movement of the arm 113 is carried sufficiently further to bring into engagement the contact terminals 116 and 118. This causes energization of the electromagnet 36, lifting the latch 31, and allowing the table 1 to withdraw for a limited distance to the right, being returned by the resetting member 43 to its position of limited reciprocation. Such amplified traverse of the table 1 and grinding wheel 5 is made use of to dress the rapidly rotating grinding wheel, since a dressing device 145 is at that time disposed in the path of said wheel, by reason of the movement of the valve member 153 to the right, resulting in movement of the piston 156 and consequently rearward motion of the lever 147, all as previously set forth. It should be particularly observed, that the dressing operation

on the wheel takes place only after the pressure on the wheel spindle 6 has been reduced. This enables the amount of dressing of the wheel 5 to be more accurately determined, 5 since there is no excessive spring in the spindle 6 as it leaves the workpiece.

It has already been described how motion of the dressing controlling lever 147, resulting in turning of the shaft 149, slows down 10 the travel of the table 1 by moving the valve member 172 to the right, Fig. 15. Movement of this valve member, as likewise described, covers up the port 235 and connects the port 232 to the exhaust port 236, thus exhausting 15 the fluid from the right hand side of piston 230 and allowing the gauge 221 to be urged into engagement with the workpiece under the influence of the spring 217. The control of the machine is at this point definitely 20 transferred from the cross feed mechanism and electric contacts controlled thereby, to the reciprocating gauge, and its associated mechanism, by reason of the fact that the right hand arm 238 strikes the right hand 25 arm 240 of the switch member 136 and rocks said switch member to the position shown in Fig. 1, thus removing both the bars 135 and 143 from the bars 134 and 142, and breaking the electric circuits controlled by the cross 30 slide.

The grinding wheel 5 reenters the workpiece, and reciprocates back and forth with a speed determined by the valve 180, which is repositioned according to the setting of 35 the nuts 169 and 168, but nevertheless restricts the fluid to keep the table 1 travelling at a slow rate of speed, and maintains the pipe 231 in connection with the exhaust port 236 so that the gauge will be allowed to reciprocate against the workpiece. At this 40 time the fine feed pawl 73 alone is active, and gradually moves the workpiece in relation to the grinding wheel. The wheel 5 having been dressed and trued, the reciprocation of the table 1 slowed down, and the cross 45 feed movement materially reduced, the final and finishing cuts of the wheel 5 are taken under ideal conditions, and the workpiece maintains true cylindrical proportions, finally coming to the desired size. When it does 50 so, the gauge 221 enters therein under the influence of the spring 217, and this causes energization of the electromagnet 37, resulting in lifting of the dog 27 causing the table 55 to run out. Just before the table dog is lifted, and as the magnet 37 is energized, the valve member 261 is moved to the right thus admitting fluid to the cylinder 267 and repositioning the cross slide. This repositioning 60 of the cross slide by retrograde movement of the involute cam 62 takes place just before the grinding wheel 5 leaves the workpiece, and therefore avoids the running of said wheel off said workpiece in contact therewith, 65 which action, as is so well known, produces a

bell mouth in the workpiece, or at least scratches therein.

The lever arm 42 being raised, the dog 27 is lifted and the table 1 runs out, to be ultimately reversed by the action of the dog 45. As the table runs out, first the cam surface 275 and then the cam surface 276 contacts with the roller 277, moving the valve member 285 by stages to the right, when viewed from the rear of the machine, and resulting successively in stopping the rotation of the chuck and causing the chuck jaws therein to open. As the chuck stops, the transferring device 49 enters therein, and as the chuck jaws open, it draws the ground workpiece from the chuck, and discharges it from the machine. When the table reaches its outermost position, the reversing dog 45 strikes the lever 42 and resets the valve member 261, and this relieves the cylinder 267 of fluid and places the cross feed mechanism in condition to be actuated. Immediately thereafter the dog 45 strikes the reversing member 25, thus reversing the direction of travel of the table 1, and causing a repetition of the cycle of operation just described, this cycle being repeated as long as there are workpieces in the magazine 47, or until such time as the operator, reading the scale 353 in connection with the pointer 352, determines that the grinding wheel 5 is no longer in condition to successfully grind workpieces, whereupon he stops the machine.

We claim,

1. In a grinding machine, a grinding wheel, workholding means, a table or carriage carrying one of said parts, cross feeding means to feed the workpiece and grinding wheel in cutting relation, a dressing device, means to procure a limited reciprocation of said carriage, automatic means to reduce the rate of cross feed between grinding wheel and workpiece before the latter reaches finished size, and means for thereafter interrupting the grinding operation, by extending the amplitude of the aforesaid reciprocation, to dress and true the grinding wheel by passing it by said dressing device, thereby to subject the grinding wheel to dressing only after the excessive wheel pressure due to preliminary rough grinding has been relieved.

2. In a grinding machine, a grinding wheel, workholding means, a table or carriage carrying one of said parts, means to procure a relative cross feed between the grinding wheel and workpiece, means to procure a limited reciprocation of said carriage, a dressing device, means under the control of the cross feeding means to first reduce the rate of said cross feed and subsequently extend the amplitude of reciprocation of said carriage, and means operative during said amplified reciprocation for rendering said dressing device effective on said wheel, thereby to subject said wheel to dressing only after the pres-

sure thereon, due to the preliminary rough grinding operation, has been removed.

3. In a grinding machine, a grinding wheel, workholding means, a table or carriage carrying one of said parts, means to procure a relative cross feed between the grinding wheel and workpiece, means to procure a limited reciprocation of said carriage, a dressing device, electromagnetic means operated by the cross feeding means to automatically reduce the rate of said cross feed, and electromagnetic means operated by the cross feeding means and coming into operation only after the first electromagnetic means operates to extend the amplitude of reciprocation of said carriage, whereby to interrupt the grinding operation on each workpiece, for subjection of said wheel to dressing only after the pressure on the grinding wheel, due to the preliminary rough grinding operation, has been removed.

4. In a grinding machine, a grinding wheel, workholding means, a table or carriage carrying one of said parts, means to procure a relative cross feed between the grinding wheel and workpiece, means to procure a limited reciprocation of said carriage, a dressing device, means under the control of the cross feeding means to first reduce the rate of said cross feed and subsequently extend the amplitude of reciprocation of said carriage, whereby to procure a dressing operation on said wheel only after the pressure on the grinding wheel, due to the preliminary rough grinding operation, has been removed, 35 a gauge adapted to contact with the workpiece, and means under the control of said gauge for procuring cessation of the grinding, by extended movement of said carriage when the workpiece comes to the desired size.

5. In a grinding machine, a chuck, a spindle to which said chuck is fastened, said spindle being rotatably mounted, a draw rod adapted to operate the workholding means in said chuck and adapted to rotate with the spindle to avoid the use of relatively rotatable connections, a cylinder, a piston in the cylinder, one of the last two being attached to the draw rod, and stationary fluid supplying means to operate the piston in the cylinder, 50 the piston revolving in the cylinder when the chuck spindle is revolved.

6. In a grinding machine, a chuck, a spindle to which said chuck is fastened, said spindle being rotatably mounted, a draw rod inside said spindle adapted to operate the workholding means in said chuck and adapted to rotate with the spindle to avoid the use of relatively rotatable connections, a gauge rod inside the draw rod and compelled to rotate with it, a cylinder, a piston in the cylinder, one of the last two being attached to the draw rod, and stationary fluid supplying means to operate the piston in the cylinder, the piston revolving in the cylinder 65 when the chuck spindle is revolved.

7. In a grinding machine a grinding wheel, workholding means, intermittently operated means comprising a rotatable member and means to turn it in one direction to procure a cross feed between said grinding wheel and said workholding means, and fluid pressure means for turning said rotatable member in the other direction to reposition the workholding means in relation to the grinding wheel at the finish of a grinding operation.

8. In a grinding machine, a grinding wheel, workholding means, intermittently operated means comprising a rotatable member and means to turn it for procuring a cross feed between said grinding wheel and said workholding means, a piston and cylinder unit, a rack connected to one of these, a gear carried by the rotatable member and meshing with the rack, and fluid pressure means to cause movement of the piston in the cylinder to reset the cross feed mechanism at the end of a grinding operation.

9. In a grinding machine, a grinding wheel, workholding means, a rotatable member movement of which procures a cross feeding movement between the grinding wheel and workholding means, a pawl, means to reciprocate said pawl, a ratchet wheel adapted to be rotated by said pawl and connected to said rotatable member, a cylinder and piston unit, connections between said cylinder and piston unit and said rotatable member, fluid pressure means to operate said piston and cylinder unit to reposition said rotatable member, means to hold said pawl out of engagement with the ratchet wheel during the repositioning movement aforesaid, said means including a latch mechanism, and automatic means to thereafter release the latch whereby to permit a further cross feeding movement in a subsequent grinding operation.

10. In a grinding machine, a cross feeding mechanism including a ratchet wheel, a pawl, means to reciprocate said pawl, an electromagnet which when energized draws the pawl away from the ratchet wheel, an automatic latch to hold the pawl in spaced relation to said ratchet wheel, and other electromagnetic means to release said latch.

11. In a grinding machine, a cross feeding mechanism including a ratchet wheel, a pair of pawls, means to reciprocate said pawls, a pair of electromagnets, one for each pawl, which when energized draw their respective pawls away from the ratchet wheel, means to successively energize the electromagnets, automatic latches to hold the pawls in spaced relation to said ratchet wheel, and other electromagnetic means to release both latches.

12. In a grinding machine, a rotatable gauge, means operable at a predetermined point in the grinding of each workpiece for 130

making said gauge effective on the work-piece during the remainder of said grinding operation, and means for holding the gauge in retracted position during the rough grinding whereby to reduce the wear on the gauge.

13. In a grinding machine, a rotatable gauge, resilient means urging said gauge toward a workpiece held in the grinding machine, a grinding wheel, a reciprocatory table or carriage whose movement produces a relative traverse between the grinding wheel and the workpiece, means operative at a pre-determined point in the grinding of each workpiece for rendering said gauge effective on said workpiece during the remainder of said grinding operation, and means for holding the gauge in retracted position during the rough grinding whereby to reduce the wear on the gauge.

14. In a grinding machine, a rotatable gauge, resilient means urging said gauge toward a workpiece held in the grinding machine, a grinding wheel, a reciprocatory table or carriage whose movement produces a relative traverse between the grinding wheel and the workpiece, connections between said gauge and said table or carriage to urge the gauge away from the workpiece at each reciprocation of the carriage to allow the grinding wheel to contact with the work-piece for grinding, means operative at a pre-determined point in the grinding of each workpiece for rendering said gauge effective on the workpiece during the remainder of said grinding operation, and means for holding the gauge in retracted position during the rough grinding whereby to reduce the wear on the gauge.

15. In a grinding machine, a rotatable gauge, resilient means urging said gauge toward a workpiece held in the grinding machine, a grinding wheel, a reciprocatory table or carriage whose movement produces a relative traverse between the grinding wheel and the workpiece, connections between said gauge and said table or carriage to urge the gauge away from the workpiece at each reciprocation of the carriage to allow the grinding wheel to contact with the workpiece for grinding, and fluid pressure means for holding the gauge in retracted position during the rough grinding whereby to reduce the wear on the gauge.

16. In a grinding machine, a workhead, a gauge, a gauge rod carrying said gauge, resilient means urging said gauge rod in a direction to cause the gauge to contact with a workpiece, a cylinder, a piston provided by said cylinder, a member attached to the gauge rod and fluid pressure means to urge said piston against said member to hold the gauge in retracted position.

17. In a grinding machine, a grinding wheel, workholding means, a table or carriage carrying one of said parts by the

reciprocation of which a relative traverse between the wheel and a workpiece is produced, a dressing device, means to bring said dressing device into position on the line of traverse of said wheel and to coincidentally cause an amplification of said traverse, a gauge, means normally holding said gauge in retracted position away from the work-piece, and means brought into operation coincidently with the means for moving said dressing device to allow said gauge to engage the workpiece.

18. In a grinding machine, a workhead, a dressing device, a gauge in the workhead, resilient means urging said gauge into engagement with a workpiece in the work-head, other means preventing the operation of the aforesaid resilient means, means for moving said dressing device, and means responsive to the movement of the last named means for rendering ineffective said other means to allow the gauge to engage the work-piece.

19. In a grinding machine, workholding means, a grinding wheel, means for procur-ing a cross feed between said parts, a gauge, resilient means adapted to urge said gauge against a workpiece, counteracting means holding said gauge away from said work-piece, and means brought into operation by said cross feeding means for rendering ineffective said counteracting means to permit the gauge to engage the workpiece.

20. In a grinding machine, workholding means, a grinding wheel, means for procur-ing a cross feed between said parts, a gauge, resilient means adapted to urge said gauge against a workpiece, counteracting means holding said gauge away from said work-piece, means brought into operation by said cross feeding means for rendering ineffective said counteracting means to permit the gauge to engage the workpiece, and further means for shifting the control of the machine from the cross feeding means to the gauge upon rendering ineffective the said counter-acting means.

21. In a grinding machine, a workhead, a gauge in said workhead, a spring urging said gauge toward the workpiece, a piston and cylinder unit, a valve adapted to connect said piston and cylinder unit to a source of fluid under pressure, said piston and cylinder unit then holding said gauge away from the work-piece, and means to move said valve to dis-charge the fluid from said cylinder after the rough grinding is completed to allow the gauge to engage the workpiece.

22. In a grinding machine, a workhead, a draw bar for the actuation of workholding means in said workhead, a cylinder and piston unit associated with said workhead to actuate said draw bar, a clutch for the workhead, a cylinder and piston unit to actuate the clutch, a table or carriage whose movement produces

a reciprocatory traverse between the grinding wheel and a workpiece, means for shifting said table or carriage from said traversing position to an idle position, and vice versa, a valve controlling both piston and cylinder units, and means operated by movement of the table to move said valve and replace it, whereby when the table shifts to idle position, first one and then the other piston and cylinder units are actuated, to stop the chuck and open the workholding means, and when the carriage returns to transversing position said units are actuated in reverse order to close the workholding means and start the chuck in rotation.

23. In a grinding machine, a grinding wheel, workholding means, a table or carriage holding one of said parts and by movement of which a reciprocatory traverse between said parts is produced, means to extend the amplitude of said traverse to procure a dressing operation on the wheel, a fluid pressure system actuating said carriage, a valve, automatic means to move said valve to slow down the movement of said carriage during the dressing operation, means for giving said carriage a further extended movement at the finish of a grinding operation, and a second valve brought into action during said extended movement for admitting fluid to a chamber to reposition said first valve.

24. In a grinding machine, a workholding chuck, a gauge, means urging said gauge against a workpiece in the chuck to cause cessation of the grinding operation when the work comes to the desired size, means brought into operation after the gauge enters the workpiece for first opening said chuck and thereafter closing it, and automatic means brought into operation before the chuck is closed again to hold the gauge out of the vicinity of the chuck to allow a workpiece to be placed therein.
